PLAYGROUND APPARATUS AND SUPPORT FOR SWINGS OR THE LIKE

Donald D. Hock, Herrin, Ill., assignor to Turco
Manufacturing Co., Du Quoin, Ill.

Filed Aug. 14, 1974, Ser. No. 497,454

Term of patent 3½ years

Int. Cl. D21—03

U.S. Cl. D34—5 M

FIG. 1

FIG. 2

FIG. 3

FIG. 4

FIG. 5

FIG. 6

FIG. 1 is a perspective view of a playground apparatus and support for swings or the like embodying my new design;

FIG. 2 is a side elevational view thereof;

FIG. 3 is a side elevational view thereof, viewed from the opposite side;

FIG. 4 is a front elevational view thereof;

FIG. 5 is a rear elevational view thereof; and

FIG. 6 is a top plan view thereof.

I claim:

The ornamental design for a playground apparatus and support for swings or the like, substantially as shown.
